FIRE HYDRANT

Cornelius Sampson, Berkeley, Calif., assignor to East Bay
Municipal Utility District, a public corporation of California

Filed Jan. 6, 1964, Ser. No. 78,087

Term of patent 14 years

(Cl. D91—3)

FIG. 1 is a perspective view of a fire hydrant showing my new design.

FIG. 2 is a side elevation thereof.

FIG. 3 is a top plan view thereof.

I claim:

The ornamental design for a fire hydrant, as shown.
